UNITED STATES PATENT OFFICE

ISIDORE KRAMER, OF NEW YORK, N. Y.

BUTTON

Application filed October 21, 1929. Serial No. 401,312.

This invention relates to a process of making buttons for articles of clothing from strips of material such as leather or the like.

- 5 The principal object of the invention is to provide a button having a covering made from strips of leather or the like which is pre-woven before applying said covering to the body of the button.
- 10 Another object of the invention is to weave the covering from small strips of leather or the like making one unitary structure so it can conveniently be applied to the body of the button.
- 15 Another object of the invention is to make the covering from two strips of leather locked together in such a way so as to give a weaving effect.

With the above and other objects in view as will be hereinafter apparent, the invention consists in general of certain novel details of construction and combination of parts hereinafter fully described, illustrated in the accompanying drawings and specifically claimed.

In these drawings like parts are designated by like reference characters throughout the specification.

- Figure 1 is a top view of the button.
- 30 Figure 2 is an edge view thereof.
- Figure 3 is a view of one form of the covering for the button.
- Figure 4 is a view of another form of the covering.
- 35 Figure 5 is a view of one of the elements which make up the covering shown in Figure 5.

Figure 6 is a cross section of the button taken on line 6—6 of Figure 1.

40 Figure 7 is a top view of the inside of the button with the leather disk in an open position.

- Figure 8 is a view of the eye for fastening the button to an article of clothing.
- 45 Figure 9 is a similar view as Figure 7 but showing a modified form of the eye.
- Figure 10 is a section on line 10—10 of Figure 9.
- 50 Figure 11 is a modified form of the covering.

Figure 12 is one of the co-operating elements.

Figure 13 is another view of the co-operating element.

Figure 14 is another modified form of the 55 covering and

Figures 15 and 16 are the parts thereof showing them separated.

Referring now to the drawings in detail numeral 1 designates the covering of the 60 button made of four strips of leather, 2, 3, 4 and 5 woven together as shown in Figure 3. Numeral 6 designates a metal foundation for the button in the form of an inverted cup. Around this metallic cup is 65 placed the covering 1 with the edges 7 tucked inwardly.

The interior of the button is formed of a metallic cup-shaped foundation 8, the bottom of which is covered with a leather disk 70 9. This disk is larger in diameter than the cup 8 so that the edge 10 can be tucked inside the button as shown in Figure 6.

Means are provided to fasten the button to an article of clothing consisting of an 75 eye 11 made from one piece of material and anchored in the interior of the button with the shank portion 12 protruding outwardly. One end of the eye is formed with an arrow-shaped portion 13 while at the 80 opposite end is formed a disk portion 14 having a slot 15 cut therein. To form a loop the arrow-shaped end is passed through the slot 15 and locked in place as shown in Figures 6 and 7. The cup-shaped foundation 8 and the leather disk 9 are formed with slots 16 so that the shank of the eye can pass through.

In finishing and assembling the button the various elements are made into two portions. The metal foundation 6 with its covering 1 forms one portion while the cup 8 with the leather disk 9 and the eye 11 positioned in place forms the second portion. The two various assemblies are then placed 90 in a powerful die and given a permanent set so that the two portions are interlocked as shown in Figure 6 and form together a strong and long lasting button which will 95 keep its shape indefinitely.

In Figures 4 and 5 is shown a modified form of the covering illustrated in Figure 3 consisting of two A-shaped portions 17 formed with slots 18 and locked together into one unitary structure. If desired the two portions can be glued together where they overlap so as to prevent any accidental disassociation of the parts while being handled.

10 In Figures 9 and 10 is shown a modified form of the means for fastening the button to an article of clothing consisting of an eye 19 having a pair of wings 20 at the top which anchor themselves in the cup 8 against any outward pull.

15 In Figures 11, 12 and 13 is shown another modification of the covering. The purpose of this form of covering is to prevent any hole appearing at the center. It will be noticed that the portion 21 is the same as any of the elements shown in Figure 4. However, the co-operating portion 22 is different in that two slots 23 and 24 as wide as the legs of element 21 are formed therein. When the two parts are locked together the center 25 will show a solid wall and thereby improve the appearance of the button. The modified form of covering shown in Figures 14, 15 and 16 comprises 20 two elements 26 and 27. Element 26 is provided with slots 28 for the legs 29 of its associate element to pass through.

25 By making the covering in the manner disclosed smaller strips of leather can be used and thereby decrease the cost of manufacture.

30 It will thus be seen that I have provided a novel method of making a button from leather or the like which has a pleasing appearance and is substantially indestructible.

35 The foregoing disclosure is to be regarded as descriptive and illustrative only, and is not a limitation of the invention, of which obviously an embodiment may be made including many modifications without departing from the general scope herein indicated and noted in the appended claims.

40 Having described my invention, I claim:

45 1. In a button of the class described, the combination of a covering, of a foundation therefor, said covering made from four equal pieces of material woven together and placed around said foundation with the edges tucked inwardly.

50 2. In a button of the class described, the combination of a covering, of a metal cup-shaped foundation therefor, said covering made from several pieces of material woven together and placed around said foundation with the edges turned inwardly, a metallic cup-shaped element provided at the bottom with a flexible covering, an eye having one end anchored in the interior of the button in the opposite end protruding outwardly 55 of said cup, said metallic cup and its cover-

ing adapted to fit into the hollow of the said cup-shaped foundation, and means to give the structure a permanent set by subjection to pressure.

3. In a covering for a button comprising two pieces of material woven together forming a unitary structure, said pieces split in half throughout most of their length forming two legs, the legs of one of said pieces adapted to pass through the split of the other said piece and be locked together.

70 75 In testimony whereof I affix my signature.
ISIDORE KRAMER.
